UNITED STATES PATENT OFFICE.

GUSTAV STAIB, OF TOMPKINSVILLE, NEW YORK.

DESIGN FOR A BASE FOR METAL CLAMPS.

SPECIFICATION forming part of Design No. 25,051, dated January 14, 1896.

Application filed September 21, 1895. Serial No. 563,258. Term of patent 14 years.

To all whom it may concern:

Be it known that I, GUSTAV STAIB, of Tompkinsville, Richmond county, New York, have invented and produced a new and original Design for Bases for Metal Clamps, of which the following is a specification, reference being had to the accompanying drawings, in which—

Figure 1 is a rear perspective view of my newly-designed base for metal clamps, and Fig. 2 is a front perspective view thereof.

The leading feature of my design consists of a base for metal clamps having a foot and a pair of parallel arms that extend from the

foot first upward and then forward and 15 downward.

a is a foot, from the rear end of which project a pair of parallel arms *b*. The arms *b* extend from the foot *a* first upward and then forward and downward and terminate in a 20 pair of eyes *c*.

What I claim is—

The design for a base for metal clamps, substantially as herein shown and described.

GUSTAV STAIB.
